TELEVISION SYSTEM

Bernard Cioffari, New Rochelle, N. Y., assignor to
Radio Corporation of America, a corporation
of Delaware

Application April 1, 1929, Serial No. 351,488

15 Claims. (Cl. 178—6)

The present invention relates to television systems, and, more particularly, to a method and means for scanning and reproducing a television subject in such systems.

In the prior art, so far as I am aware, it has hereinbefore been customary to utilize, for the purpose of scanning and reproducing, disks of rather large size in order to provide sufficient detail by which the television picture received may be readily recognized and be of considerably clearer detail. It has been found, however, with the use of such disks, which may be either of the lens or mirror type, that objectionable features have been occasioned by reason of the fact that such disks were very cumbersome and found to have large moments of inertia, and were incapable of being driven by any small type of synchronous motor such as could be readily driven from the small amount of energy received over a television transmission system for the purpose of synchronizing. With the use of large motors, such as are necessary for the larger size disks, considerable difficulties in synchronizing have been occasioned by reason of the fact that any synchronizing action produced on the drive motor for the disk must be by way of a small synchronous motor, or similar compensating element, used to control the main drive motor. A small motor of this type in order to synchronize the rotating elements of the transmitter must either exert a retarding or advancing action upon the main drive motor, and considerable difficulties have been occasioned in arranging a set up by which this type of synchronizing could readily be accomplished.

Also, with the use of large disks such as are necessary to gain the desired amount of detail, difficulty has been occasioned in arranging a compact installation such as would be convenient for use in homes and necessary for commercialization of television apparatus.

It is, therefore, an object of my invention to produce an arrangement by which the difficulties occasioned by the use of large disks for television scanning and reproducing are substantially eliminated.

A further object of my invention is to provide a method and means for scanning and reproducing television subjects in which the rotating elements necessary have been materially reduced in size so that they may be driven by the smallest types of synchronous motors which, in turn, may be synchronized by the use of a small amount of energy such as is obtainable from a synchronizing

signal simultaneously transmitted with the television.

A further object of my invention is to provide a method and means for scanning television subjects which will materially reduce the installation expense, since the parts thereof have been reduced to a minimum, and, consequently, less expense for lenses if a lens disk be used, or mirrors, if a mirror disk be used, is necessary.

Still another object of my invention is to provide a method and means by which the speed at which the television subject may be scanned may be considerably increased, and, thus, the objectionable effects of flicker in the reproduced image substantially avoided. Such arrangement is possible with a considerable reduction in the size of the moving elements which are thus capable of higher speeds, and which can be driven by smaller motors, and by which it is possible to considerably increase the optical efficiency of the entire system.

Still another object of my invention is to provide a method and means for scanning and reproducing television subjects which is simple in its construction and arrangement of parts, a system which is durable, compact, conveniently installed, readily set up, easily operated, efficient in its use, and readily adapted to use in conjunction with the present types of transmitting and receiving circuits and apparatus.

Still other and ancillary objects will become apparent and at once suggest themselves to those skilled in the art to which the invention relates by a reading of the following specification taken in connection with the accompanying drawing, wherein:

Fig. 1 illustrates an arrangement disclosing the principle of my invention utilizing a small disk having only four reflecting surfaces;

Fig. 2 illustrates conventionally a form of apparatus especially suited to the purpose and arrangement of my invention;

Fig. 3 diagrammatically illustrates a further arrangement of the invention;

Fig. 4 diagrammatically illustrates the paths by which the television subject is exposed to scanning rays of light, or by which the paths of light of varying intensity, controlled in accordance with the intensity of light and shadow on the television subject, may be reproduced;

Fig. 5 discloses a modification of my invention as applied to a lens disk type of scanning element in contrast to the mirror disk disclosed by Figs. 1, 2 and 3;

Fig. 6 illustrates in conventional manner the

arrangement of the reflecting surfaces as tilted in the vertical plane; and,

Fig. 7 conventionally illustrates the manner in which the picture is rebuilt when using a disk and 5 cooperating fixed mirror surfaces of the type shown by Fig. 2.

Now particularly referring to the accompanying drawing, it will be recognized that if a large size disk of the mirror type be used, for example, 10 and a sixty line detail picture be desired, that with the type of scanning system hereinbefore used in connection with television developments, it was necessary to provide sixty distinct reflecting bodies placed about the periphery of a disk 15 so that each successive mirror would be tipped at an angle of six degrees with respect to the preceding mirror in the plane of the disk. With such a system, supposing that sixty mirrors are used about the disk, it will be seen that beams 20 of light reflected from two successive mirrors will be at an angle of twelve degrees with respect to each other, since when light is reflected upon a mirror, if the plane of the mirror is rotated through a given angle, the reflected beam of light 25 will be rotated through twice that angle. This would mean that as the disk is rotated, only twelve degrees of rotation of the beam of light reflected by any one mirror is capable of utilization because of the fact that the light reflected 30 by adjacent mirrors will follow the light reflected by the first mirror after the first light beam has traveled through an angle of twelve degrees. Therefore, if it were possible to utilize more than a twelve degree angle of the reflected light beam, 35 it would also be possible to reduce the size of the scanning disk element.

Now referring particularly to Fig. 1, suppose, for example, that only four mirrors, 1, 2, 3 and 4, were arranged about the periphery of a scanning 40 disk. Then, as this disk rotates in the direction shown by the arrow, and a mirror moves from the position *a* to the position *b*, the light reflected by the mirror will rotate through a wide angle, and turn from the position *a'* to the position *b'*. 45 To utilize the entire angular sweep between *a'* and *b'*, it would be necessary to place a circular or cylindrical screen in the path of the reflected light beams. Such a system is, of course, not particularly feasible, and even aside from this 50 feature, only four lines on the screen would be produced. However, a simple way to surmount such a difficulty is to arrange a plurality of stationary mirrors about the arc of a circle upon which the light is reflected, and to so tip and tilt the mirrors that each mirror will reflect the light therefrom to the same screen.

To refer now more particularly to Fig. 2, showing a preferred form of arrangement of my invention, assuming that instead of using a disk 60 composed of only four mirror elements, as shown by Fig. 1, that the number of mirror elements were substantially increased, and, for example, as shown by Fig. 2, that these elements were increased to twelve mirrors placed about the periphery of the disk, and each tilted at a slightly different angle to the plane of the disk. This would mean that, as the disk is rotated in the direction shown by the arrow, twelve distinct lines of scanning will be produced upon a screen 65 70 positioned in the path of reflected light beams, and since the mirrors 1, 2, etc., are placed at an angle of thirty degrees with respect to each other the total angular rotation produced by each distinct mirror will cover the arc of sixty degrees 75 before the reflected light from the next mirror

comes upon the screen. With such an arrangement, the screen would then have to be a cylindrical surface covering an arc of sixty degrees in order that there would be only one spot on the screen at any one instant, and such a system would then provide a screen covered by twelve distinct lines of scanning.

Suppose, for example, that instead of placing a screen, such as the planar dotted outline screen, 10 in the path of the light beams which are reflected from the disk 11 during the rotation thereof, a plurality of narrow mirrors 12, 13, 14, 15 and 16 each covering 12 of the 60 degrees should be placed in the path of the rotating light beam reflected from the mirror surfaces 1, 2, 3, etc., of the disk 11. Then, as the disk 11 rotates the beam of light reflected from each of the mirrors 1, 2, 3, etc., in sequence will sweep across the arc of a circle from point *c* to point *f*. So arranged, it can be appreciated that each mirror surface arranged about the arc of the circle 10 will produce on a screen 17 arranged to receive the light received from the mirrors a single spot of light extending from points somewhat to the right and left, respectively, of the points *f'* and *c'* on the viewing surface 11, it being understood from Fig. 3 that mirror wheel 11 is positioned outside the light path from reflectors 12 to 16 and screen 17. However, if it is desired to take advantage of the principle of invention 20 illustrated herewith and in order to produce more than 12 parallel lines of light traced upon the screen 17 by each single rotation of the mirror wheel 11 (assuming that 12 mirror surfaces are provided thereon) each of the separate and 25 individual mirrors 12, 13, 14, 15 and 16 is set and tilted at slightly different angles, both as regards horizontal and vertical tilting, with respect to each other so that as any one beam of light is caused to travel across the screen 17 a 30 path of light will be traced between the points *f'* and *c'* as the light beam reflected from any of the elemental surfaces 1, 2, 3, etc., reaches each of the individual mirrors 16, 15, 14, etc. This 35 principle has been conventionally illustrated by 40 Fig. 2 wherein, for example, light beam reflected from the mirror surface 1 to strike or impinge upon the mirror 16 will first be reflected as it strikes the mirror surface along a path *cf'* and 45 this path will progressively change in the direction of the point *c'* on the screen 17 until the light beam strikes the point *d*, just prior to the instant at which the light beam from reflector 1, for example, reaches the mirror surface 15, in 50 which case the path of reflected light will be 55 that designated by the line *dc'*. The light beam reflected from the mirror surface 1 then immediately passes on to the next mirror surface 15 which is tilted as above described with respect to the mirror surface 16 and the light path traced 60 across the screen 17 will be first along the direction *df'* and as the light beam reflected from the mirror 1 then approaches the mirror 14 the light path will finally change so that it extends from 65 the left hand edge of the mirror 15 toward the point *c'*. These various light paths are indicated in Fig. 2 by the reference numeral corresponding to that of the mirror surface from which the light beam is reflected. In accordance 70 with this description, for each 30 degree rotation of the mirror wheel 11 there will be traced on the screen 17 five separate light paths all 75 extending between the points *f'* and *c'*.

By Fig. 4, I have shown diagrammatically, a diagram showing the individual paths by which 75

the light beams are reflected, and referring now to Fig. 4, it will be seen that the light beam *a* as reflected by the mirror 1, for example, is widely separated from the light beam *b* reflected by the mirror 2, for example, and that due to the angular tilting of each of the individual mirrors composing the periphery of the disk 11 about the axis of the disk 11, the reflected light beams traverse parallel paths widely separated from each other.

However, as the light beam reflected by the disk 1, for example, strikes the mirror surface 16, it is reflected back upon the screen 17 along a path designated as *a*₁ on Fig. 4, and as the same light beam reaches the mirror 15, it is reflected along a path *a*₂, and as the disk 11 is rotated so that the reflected light beam from the surface 1 has reached the mirror surface 12, the path of the reflected light beam projected towards the screen 17, has assumed a position *a*₅ after which the mirror surface 2 positioned about the periphery of the disk 11 is in the path of the projected light from the source 18, which, for example, may be a glow lamp illuminated by incoming television signals for the purpose of reproducing, or may be an arc source of light, if the system is to be used as an analyzing system for transmission purposes, and the subject for transmission is then positioned at the point where the screen 17 is located, and the path of light initially traced by light from the source 18 being reflected from the mirror surface 2 towards the mirror 16, will be along the path *b*₁, and following the example shown above in connection with the mirror 1, the successive paths of illumination of the screen 17 will be along the lines *b*₂, *b*₃, etc. This scanning action is then continuously repeated until the projected light from the source 18 has illuminated each and every mirror positioned about the periphery of the disk 11, and after the last mirror has been turned so as to come into the path of the light rays issuing from the source 18, the scanning or reproducing process will be repeated, and follow the system conventionally illustrated and described in connection with Fig. 4.

Now referring more particularly to Fig. 3, I have shown an elevation view schematically describing the system hereinabove described in connection with Figs. 2 and 4, and light from the source 18 is shown as projected upon a mirror 7 located on the periphery of the disk 11, and then reflected to the center mirror 14 of the fixed bank of mirrors, each tilted at a different angle with respect to the horizontal and vertical axis, and arranged about the arc of a circle. It is thus seen that the reflected beam of light from the mirror surface 7 of the disk 11 and the fixed mirror 14 will trace a path designated as *g*₃ and project itself upon the screen 17.

Since a mirror disk arrangement, and a lens disk arrangement are substantially similar and equivalent, by Fig. 5, I have shown a lens disk 21 mounted on shaft 22 through which light from a similar source 18 is projected and directed along a bank of mirrors arranged similarly to those shown and described in connection with Fig. 2. As the disk 21 rotates in the direction of the arrow, the light beams issuing therefrom may be arranged to trace similar parallel paths across the screen 17 to those shown and described in connection with the above named figures of the drawing.

By Fig. 6 I have shown conventionally the relationship between the various mirrors 12, 13,

14, 15 and 16 with respect to their inclination to the vertical plane. By this figure, it is to be noted that the arrangement shown is considerably exaggerated for the purpose of emphasis, and while the mirrors 12, 13, 14, 15, and 16 are shown as each being tilted 1¼' more than the other with respect to the vertical plane, this is, of course, merely given by way of example and illustration rather than in any limiting sense. The vertical tilt of the mirrors is, of course, dependent upon the size of reproduced picture which is to be desired, but if a case is assumed where twelve rotating and five fixed mirrors are used, and the fixed mirrors are approximately 8" away from the rotating mirrors and the size of picture to be produced is about 12" x 10", the angle assumed has been found to be satisfactory, although other angles of inclination may be resorted to without departing from the spirit and scope of the invention.

Similarly, it has been assumed that the angular direction of the mirrors 13 and 15 with respect to the plane of mirror 14, and the angle of mirrors 12 and 16 with respect to the plane of mirrors 13 and 15 is 6.3 degrees. This value is also merely illustrative and should not be considered as limiting but has been found to be satisfactory for the above assumed case.

By Fig. 7 I have shown in a diagrammatic manner the picture which is produced according to my above described invention. In this figure the lines produced by the mirror surfaces 1, 2, 3, etc. of the disk 11 have been indicated by a corresponding number with an exponent corresponding to the mirror surface of the fixed reflecting body from which the light is re-directed.

From the above description, it should be understood that the system is equally adapted for use either as a transmitter scanning or a receiver scanning system, and further that the term "disk" as hereinafter used in connection with the appended claims should be regarded in a generic sense, and include mirror disks, spirally arranged lens disks, lens disks having both mirrors and prisms so arranged as to direct the issuing light beams along different parallel paths, and, in fact, all arrangements capable of producing like results, and I, therefore, do not desire to be limited in what modifications of the system I may make, but believe myself to be entitled to all modifications such as fall fairly within the spirit and scope of the invention as defined by the herein-after appended claims, wherein I claim:

Having now described my invention, what I claim and desire to secure by Letters Patent is the following:

1. The method of scanning which consists in directing light from a light source in a single beam, continuously directing said beam along an arcuate path, consecutively reflecting said beam in different planes whereby it traces a plurality of different elemental width parallel paths each covering one dimension of a picture surface which is spaced away from said arcuate path.

2. In a television system, the method of scanning which includes generating a light beam of an intensity corresponding to the intensity of light and shadow on elemental areas of a television subject, directing the produced light in a single beam, sequentially projecting the light beam along a series of predetermined spaced arcuate paths, and consecutively reflecting the light beams along a plurality of different adjacent parallel planes each covering one dimension of a picture surface and each of elemental width during periods of

change in the sequence of arcuate motions of the light beam.

3. In a television system, the method of scanning and reproducing which includes producing 5 light beams and directing the same along a pre-determined path, continuously directing the said beams along a plurality of arcuately spaced paths and successively reflecting said beam in different planes for tracing a plurality of additional paths 10 of light along a succession of transverse sections of elemental width and a length equal to one dimension of a field of view.

4. In a television system, means for producing 15 light intensities corresponding to the intensities of light and shadow on elemental areas of a television subject, means for projecting said light beams along a predetermined path, a disk for continuously changing the path of said projected light beams to a plurality of spaced parallel paths, 20 and a fixed set of mirrors for continuously deflecting the said projected light beams along successive transverse parallel paths across one dimension of a picture surface and each of elemental width interspersed between said parallel paths produced 25 by said initial changes in path of said light beams, and a screen positioned in the path of said last named reflected light beams for producing a visible image of the television subject.

5. In a television scanning system, a light 30 source, means for projecting the light issuing from said source along a predetermined path, rotating means for continuously deflecting said projected light beams along a plurality of spaced horizontal paths, means positioned in the path of said deflected light beams for successively changing the path of each of said deflected light beams into a plurality of adjacent parallel paths each of elemental width and interspersed in a vertical plane between said first named group of parallel paths 35 so as to traverse the picture area fully in one direction, and a screen means successively illuminated by all said elemental width parallel paths of light.

6. In a television scanning system, a light 45 source, means for projecting the light issuing from said source along a predetermined path, a rotating disk means positioned in the path of said projected light beams, means provided by said disk for successively projecting said light beams along 50 a plurality of spaced parallel paths, means fixed in position and located in the path of said projected light beams for controlling the said projected light beams and tracing the same along a plurality of parallel paths each of elemental width 55 and across the length of the picture surface interspersed between said first named group of parallel paths, and a screen positioned in the path of all of said reflected light beams.

7. In a television system, a light source, means 60 for projecting the light issuing from said source along a predetermined path, a rotating disk positioned in the path of said projected light beams for continuously and successively reflecting said light beams along spaced parallel paths, a fixed 65 bank of mirrors in the path of said reflected light beams for directing each separately projected light beam from said disk into a number of distinct transverse parallel sections each of elemental width and equal to the length of the field of view, and a screen positioned in the path of the reflected light from said fixed bank of mirrors.

8. In a television system, means for producing 70 light beams of predetermined intensities, means for projecting said light produced along a pre-

determined path, means for continuously changing the path of said light beams to a plurality of spaced paths, means for continuously deflecting said first named projected light beams along a series of parallel transverse paths equal to the length of the field of view interspersed between said first named paths produced by said initial change in the path of said light beams, and a screen positioned in the path of said last named reflected light beams for producing a visible 10 image of a television subject.

9. In a television scanning system, a light 15 source, means for projecting the light issuing from said source along a predetermined path, rotating means for continuously reflecting said 20 projected light beams along a plurality of spaced paths, means positioned in the path of said deflected light beams for successively changing the path of each projected light beam into a plurality of adjacent parallel lines each of elemental 25 width and equal to the length of the field of view interspersed between the said group of spaced light paths, and a screen means positioned in the path of all of said light beams for producing a visible image thereon when illuminated success- 30 sively by all of said paths of light.

10. In a television scanning system, a light 35 source, means for projecting the light issuing from said source along a predetermined path, a rotating disk means positioned in the path of 40 said projected light beams for successively projecting said light beams along a plurality of spaced paths, means positioned in the path of said light beams projected by said disk for controlling said projected light beams and tracing 45 the same along a plurality of adjacent paths each of elemental width and of a length corresponding to that of one dimension of the picture subject and interspersed between said first named spaced paths, and a screen positioned in 50 the path of all said reflected light beams so as to produce a visible image when all of said light beams are successively traced across the same.

11. In combination, a rotary scanning disk 55 for tracing a series of separated paths of light, and a plurality of fixed reflecting bodies in the path of each separate light path for so directing each successive path of light traced by the said rotary scanning disk as to form a plurality of parallel interspersed light paths each of elemental width and equal in length to one dimension of the picture.

12. In combination, a rotary scanning element for tracing a series of separated paths of light, and a plurality of fixed reflecting bodies 60 inclined with respect to each other in two planes and arranged in the path of each of the separated scanning paths for so directing each successive path of light traced by the rotary scanning element as to form a plurality of parallel 65 interspersed light paths each of elemental width and equal in length to one dimension of the picture.

13. In a television system, a rotary scanning element and a fixed independent means cooperating therewith for so directing the scanning beams from said scanning element as to successively distribute each scanning beam over a plurality of parallel paths each of elemental width and equal in length to one dimension of 70 the picture occupying the space between the successive paths normally traced by the scanning beam.

14. In a television system, a rotary scanning disk for tracing a set of paths of light across 75

- an object and a plurality of fixed reflecting bodies cooperating therewith for so directing the scanning beams from said scanning means as to successively distribute each scanning beam over 5 a plurality of adjacent parallel paths, each of elemental width and equal in length to one dimension of the picture occupying the space between the successive paths normally traced by the scanning beam.
- 10 15. The method of television scanning which includes directing light from a source in a single beam, directing the beam arcuately in sequence along a series of spaced light paths of a number materially less than sufficient to obtain sharp detail in image reproduction across a predetermined area, and progressively reflecting the beam 5 in sequence along different parallel paths each equal in length to one dimension of a field of view and each of elemental width during each arcuate motion for causing increased detail in image reproduction by interspersing additional light paths within the area between initially 10 traced arcuate light paths.

BERNARD CIOFFARI.
